UNITED STATES PATENT OFFICE.

LOUIS T. LAPAUGH, OF UTICA, NEW YORK, ASSIGNOR OF TWO-THIRDS TO
EDWIN D. GRAY AND WILLIAM R. DONALTY, OF SAME PLACE.

NURSING-BOTTLE.

SPECIFICATION forming part of Letters Patent No. 608,053, dated July 26, 1898.

Application filed August 14, 1897. Serial No. 648,286. (No model.)

To all whom it may concern:

Be it known that I, LOUIS T. LAPAUGH, a citizen of the United States, residing at Utica, in the county of Oneida and State of New York, have invented certain new and useful Improvements in Infants' Nursing-Bottle Attachments; and I do hereby declare the following to be a full, clear, and exact description of the invention, such as will enable others skilled in the art to which it appertains to make and use the same.

This invention relates to nursing-bottle attachments; and the object in view is to provide means whereby a nursing-bottle may be secured at any desired place and to any convenient article for preventing the bottle from dropping and breaking and also for keeping the bottle in sight and reach of the child, thus obviating the need for constant care on the part of an attendant.

The detailed objects and advantages of the invention will appear in the course of the subjoined description.

The invention consists in an improved attachment for nursing-bottles embodying certain novel features and details of construction and arrangement of parts, as hereinafter fully described, illustrated in the drawings, and incorporated in the claims hereto appended.

In the accompanying drawings, Figure 1 is a perspective view showing the attachment complete and applied to a bottle. Fig. 2 is a detail perspective view of the bottle-holding frame, with the strap and bottle removed.

Similar numerals of reference designate corresponding parts in the views.

The improved bottle-holder contemplated in this invention is constructed in the main from a single link of wire. In forming the bottle-holding frame the wire at one extremity is bent to form a loop 1. It is then bent to form a portion 2, which passes half-way around the base of the bottle, forming one-half of the lower loop or receptacle, in which the bottle sets. Upon reaching the middle line at one side of the bottle the wire is bent at the point 3 and extended upward for a distance equal to the width of the strap to be employed in attaching the bottle and frame to any given object. After forming the strap-

receiving portion (indicated at 4) the wire is offset transversely, as indicated at 5, and is brought to bear against the side of the bottle, when it is again extended upward, as indicated at 6, along the side of the bottle until it reaches a point near the bottle-neck. The wire is now bent at the point 7 and extended a short distance, as indicated at 8, after which it is recurved, as at 9, to form a spring-clasp 60 which passes a little more than half-way around the neck of the bottle, so as to obtain a firm spring or yielding hold thereon. After recurving the wire it is bent back to form a substantially semicircular portion 10, which 65 extends more than half-way around the neck, where a second spring-clasp 11 is formed similar to that 9 just described. The wire is then extended downward alongside of the neck, as indicated at 12, then offset, as at 13, to form a 70 space for the strap, then extended downward, as at 14, then given one complete turn or bend to form a loop 15, which enters and engages the initial loop 1, after which the terminal portion of the wire (indicated at 16) is 75 bent to extend around the lower portion of the bottle to form the remainder of the lower loop or receptacle, in which the bottle sets, and the extremity 17 of the wire is then bent around the initial portion of the wire at the 80 point where the bend 3 occurs.

18 designates a strap of any suitable size and length, having at its opposite ends buckles 19 to receive smaller auxiliary straps 20, by means of which the bottle and holding device may be securely attached to a bed, crib, carriage, or to the infant itself.

From the foregoing description it will be seen that both the bottle and strap are normally held in the wire frame. In order to 90 remove the bottle for cleansing purposes or refilling, the spring-clasps about the neck of the bottle are pressed out of engagement therewith, when the bottle may be lifted out of the lower loop or receptacle and then the 95 strap may be likewise removed. In reassembling the parts the strap is first placed in position, and then the base of the bottle is set into the lower loop or receptacle, whereupon the spring-clasps of the holder are 100 snapped around the neck of the bottle, thus holding the bottle securely. The offsets in

the upwardly-extending portions of the wire at the sides of the bottle form shoulders for preventing the upward movement of the strap, while the loops at the lower portions 5 of the latter prevent the downward escape or movement of said strap.

It will of course be understood that the bottle-holder above described may be made of any size and gage of wire and that it may be 10 varied to suit bottles of different shapes and sizes; also that other changes in the form, proportion, and minor details of construction may be resorted to without departing from the principle or sacrificing any of the advantages of the invention.

Having thus described the invention, what is claimed as new, and desired to be secured by Letters Patent, is—

1. A bottle-holder, embodying a wire frame 20 bent to form a lower loop for embracing the base of the bottle, an upper pair of oppositely-located spring-clasps for engaging the bottle-neck on opposite sides, and offsets provided for the reception of a strap wherewith

the bottle and frame may be secured to a 25 given object, substantially as described.

2. A bottle-holder, composed of a piece of wire looped and bent to form a lower receptacle for the base of a bottle and comprising upwardly-extending portions which pass 30 along the opposite sides of the bottle and upward to the neck thereof, the wire being bent to form a semicircular portion which extends more than half-way around the neck of the bottle and forms oppositely-located spring- 35 clasps for engagement with the neck, the upwardly-extending portions of the frame at the sides of the bottle being offset to form spaces for the reception of an attaching-strap, substantially as described.

In testimony whereof I have signed this specification in the presence of two subscribing witnesses.

LOUIS T. LAPAUGH.
